UNITED STATES PATENT OFFICE.

GEORGE T. PRITCHARD, OF NORFOLK, VIRGINIA.

TAG-ADDRESSING MACHINE.

1,070,176.

Specification of Letters Patent.

Patented Aug. 12, 1913.

Application filed July 19, 1912. Serial No. 710,497.

To all whom it may concern:

Be it known that I, GEORGE T. PRITCHARD, a citizen of the United States, residing at Norfolk, in the county of Norfolk and State of Virginia, have invented certain new and useful Improvements in Tag-Addressing Machines, of which the following is a specification.

My invention relates to machines for addressing tags, and has for its object the provision of a hand operated device adapted for printing a plurality of tags from a single stencil, the printing device being connected with a single delivery tag carrier by which the tags are removed from a receptacle and carried into position for the impression by the stencil and then delivered from the carrier mechanism when returned to receive and deliver another tag.

My invention will be described in detail hereinafter and illustrated in the accompanying drawings, in which,

Figure 1 is a top plan view of my improved tag addressing machine, showing the parts in position preparatory to removing a tag from the container before being carried into position to be printed; Fig. 2, a section on the plane indicated by the line 2—2 of Fig. 1, the plate 24 being omitted; Fig. 3, a front elevation; Fig. 4, a rear elevation; Fig. 5, a section on the plane indicated by the line 5—5 of Fig. 1; and Fig. 6, a section on the plane of section shown in Fig. 2 showing the parts in a printing position.

My invention relates to the art of printing address tags employing a stencil cut in the ordinary manner in impression paper or fabric in which the stencil is fixedly secured to a frame carrying a printing pad and so mounted that the impression is made through the stencil, it being the purpose to use the stencil to print a number of tags therewith and then to remove the stencil from the holder and replace it with another address stencil and repeat the operation with the new stencil.

In the drawings, I have shown my improved machine and in the description will refer by similar reference characters to corresponding parts throughout the several views therein.

My improved tag addressing machine is mounted on a suitable base 1 having the side plates 2 and a rear plate 3 secured thereto. Secured to the rear plate 3 by means of the

brackets 4 and 5, is a receptacle 6 open at its upper and lower ends and adapted to receive the blank tags to be operated upon, said tags being held in said receptacle by means of fingers 7 secured to the rear plate 3 and extending across the lower end of said receptacle.

Slidably mounted in grooves 8 in the side members 2 is a plate 9 that operates as a delivery plate and also the platen for receiving and holding the tags delivered from the receptacle 6 during the printing operation. Secured to the under side of the plate 9 are spring fingers 10 having their rear extremities bent upwardly as shown at 11 and extended through notches 12 in the rear extremity of the plate 9, said fingers operating when the plate 9 is in its rearmost position as shown in Figs. 1, 2, 4 and 5, to engage the lowermost tag in the receptacle 6 to deliver it from said receptacle by the mechanism to be hereinafter described. The lower margins of the front and rear sides of the receptacle 6 are formed with aligned notches 13 to permit reciprocation of the plate 9 as heretofore stated.

The plate 9 is actuated by means of angular levers 14 pivotally mounted on the side plates 2 as shown at 15 and have pins 16 thereon that engage slots 17 in arms 18 pivotally mounted on said plates 2 as shown at 19, said arms 18 being also provided with slots 20 near their lower free extremities that engage pins 21 secured to ears 22 mounted on the rear margin of the plate 9 and adjacent to the two side margins thereof. Levers 14 have their free terminals connected by means of a rod 23 that is utilized as a handle for operating said levers and has a bar 24 pivotally mounted thereon as shown at 14^a, and has a printing plate 25 mounted thereon by means of the bracket arms 25'. The printing plate 25 has secured thereto an ink pad 26 on which is adapted to be mounted a stencil 27 secured in position on said pad by means of a frame 28 removably engaging said plate 25.

By pivoting the bar 24 on the levers 14, it will be apparent that the printing plate 25 with the ink pad 26 is always in a horizontal position, while the device is in operation, so as to prevent the ink from running to the edge of the pad and dripping off, and furthermore that the printing plate 25 may be turned upwardly when the machine

is not in operation to prevent dripping of the ink, and also when it is desired to replace the stencil thereon with a new one.

Secured to the front side of the receptacle 6 are horizontal fingers 29 that are adapted to engage the printed tag when the plate 9 is moved from the printing position, and to deliver said tag on to the inclined plate 30 from whence it is delivered from the machine.

31 indicates springs connecting arms 18 with the side members 2, said springs operating to move said arms rearwardly and thereby move the plate 9 to its rearmost position and the levers 14 to their elevated positions.

In operation, the receptacle 6 being filled with blank tags laid face upward, and the machine being in the position shown in Figs. 1, 2, 3, 4 and 5, the levers 14 are compressed downwardly by manual pressure on the cross bar 23. By such movement of the levers 14 downwardly, the arms 18 are swung in a forward direction and by such forward movement, slide the plate 9 from under the receptacle 6 carrying therewith the lowermost tag and by the time the levers 14 assume the position shown in Fig. 6, the plate 9 will as shown in said Fig. 6, be under the printing plate 25 so that the tag thereon will receive an impression through the stencil 27 mounted on said printing plate. When pressure on the cross bar 23 is released the springs 31 will as stated above, raise the levers 14 to their uppermost positions and at the same time move the plate 9 to its rearmost position. When the plate 9 moves to its rearmost position as stated, the printed tag thereon will be pushed from the plate by engaging the fingers 29 and will slide down the inclined plate 30.

Having thus described my invention, what I claim is:—

1. In a tag addressing machine, a receptacle suitably mounted and adapted to hold a plurality of tags arranged face upward, a horizontally reciprocating plate operating beneath said receptacle and adapted to engage the lowermost tag when operated, arms suitably pivoted and operatively connected to said plate, bell crank levers pivotally mounted and operatively engaging said

arms, and a printing mechanism secured to said levers, said horizontally reciprocating plate operating to hold the tag while being printed. 55

2. A tag addressing machine comprising a receptacle adapted to hold a plurality of tags arranged face upward, a plate mounted 60 to reciprocate under said receptacle, spring fingers secured to said plate and having upturned ends adapted to engage the lowermost tag in the receptacle and deliver it therefrom, arms pivotally mounted and operatively engaging said plate, bell crank levers also pivotally mounted and operatively engaging said arms, and a printing mechanism mounted on said levers, said levers when moving into a printing position 70 adapted to actuate said plate to deliver a single tag thereon into position for and supporting it during impression by the printing mechanism carried by said levers. 65

3. A tag addressing machine comprising 75 a receptacle suitably mounted, fingers suitably secured and located beneath said receptacle, said receptacle being adapted to receive a plurality of tags arranged face to face and resting upon said fingers, a plate 80 slidably mounted and operating beneath said receptacle, spring fingers secured to said plate and adapted to engage a single tag within the receptacle and to deliver it therefrom, arms pivotally mounted and operatively engaging said plate, levers also pivotally mounted and operatively engaging said arms, a printing mechanism mounted on said levers, said levers being adapted to actuate said plate to deliver a single tag 90 thereon from said receptacle into position to be printed by the printing mechanism mounted thereon, fingers secured to the forward side of said receptacle and adapted to engage the tag on the plate for printing 95 when the plate is moving into position under the receptacle, and an inclined plate located adjacent to said fingers to receive the tag delivered from the plate. 95

In testimony whereof I affix my signature 100 in presence of two witnesses.

GEORGE T. PRITCHARD.
